UNITED STATES PATENT OFFICE.

ORESTE SCALISE, OF CHICAGO, ILLINOIS.

DESIGN FOR A DUSTPAN.

59,131.

Specification for Design. Patented Sept. 20, 1921.

Application filed April 30, 1921. Serial No. 465,846. Term of patent 7 years.

To all whom it may concern:

Be it known that I, ORESTE SCALISE, a subject of the King of Italy, residing at Chicago, in the county of Cook and State of Illinois, have invented a new, original, and ornamental Design for a Dustpan, of which the following is a specification, reference being had to the accompanying drawings, wherein—

Figs. 2 and 3 are sectional views taken on the line 2—2 and 3—3 respectively, of Fig. 1.

I claim as my invention:

The ornamental design for a dustpan, as shown.

ORESTE SCALISE.
